UNITED STATES PATENT OFFICE.

CARL H. ZWERMANN, OF NEWARK, OHIO.

KILN.

1,308,973.

Specification of Letters Patent.

Patented July 8, 1919.

Application filed March 27, 1919. Serial No. 285,475.

To all whom it may concern:

Be it known that I, CARL H. ZWERMANN, a citizen of the United States, residing at Newark, county of Licking, State of Ohio, 5 have invented certain new and useful Improvements in Kilns, of which the following is a specification.

This invention relates to improvements in kilns.

10 The main objects of this invention are:

First, to provide an improved kiln of the tunnel type in which the firing temperatures or temperatures in the firing zone may be effectively controlled.

15 Second, to provide in a kiln of the tunnel type an improved means for controlling the heat in the firing zone to secure variations or sub-zones within the firing zone.

Third, to provide in a kiln an improved 20 preheating means.

Fourth, to provide a kiln in which a very large proportion of the heat units of the fuel consumed are utilized.

Fifth, to provide an improved kiln of 25 large capacity.

Sixth, to provide an improved kiln which, considering its capacity, is economical to construct and requires but little skilled labor in its operation.

30 Further objects, and objects relating to structural details, will definitely appear from the detailed description to follow.

I accomplish the objects of my invention by the devices and means described in the 35 following specification. The invention is clearly defined and pointed out in the claims.

A structure which is a preferred embodiment of my invention is clearly illustrated in the accompanying drawing, forming a 40 part of this specification, is which:

Figure I is a horizontal section of a tunnel kiln embodying the features of my invention taken on a line corresponding to line 1—1 of Figs. II, III, VI, VII, VIII, and IX, 45 the figure consisting of three complementary sections.

Fig. II is a vertical longitudinal section on a line corresponding to line 2—2 of Figs. I, IV, V, VI, VII, VIII, and IX, the figure 50 consisting of three complementary sections.

Fig. III is a vertical longitudinal section on a line corresponding to line 3—3 of Figs. I, IV, V, VI, VII, VIII, and IX, the figure 55 consisting of three complementary sections.

Fig. IV is a transverse vertical section 55 on lines corresponding to lines 4—4 of Figs. I, II and III.

Fig. V is a transverse vertical section on lines corresponding to lines 5—5 of Figs. I, 60 II, and III.

Fig. VI is a transverse vertical section on lines corresponding to lines 6—6 of Figs. I, 65 II, and III.

Fig. VII is a transverse vertical section on lines corresponding to lines 7—7 of Figs. I, 70 II and III.

Fig. VIII is a transverse vertical section on lines corresponding to lines 8—8 of Figs. I, 75 II and III.

Fig. IX is a transverse vertical section on lines corresponding to lines 9—9 of Figs. I, 80 II and III.

Fig. X is an enlarged detail longitudinal section on a line corresponding to line 10—10 of Fig. I.

Fig. XI is an enlarged detail vertical longitudinal section through the flues on line 85 corresponding to line 11—11 of Fig. VII.

Fig. XII is a detail horizontal section showing a modification adapted for the burning 90 of liquid fuel.

Fig. XIII is a detail section on a line corresponding to line 13—13 of Fig. XII.

In the drawing similar reference characters refer to similar parts throughout the 85 several views, and the sectional lines are taken looking in the direction of the little arrows at the ends of the section lines.

In the accompanying drawing various features are shown more or less conventionally, and without particular regard to dimensions and the relative proportions of the parts, the accompanying drawings being 90 illustrative only.

Referring to the drawings, I provide a 95 pair of tunnels, designated generally by the numerals 1 and 2, the tunnels being substantial duplicates arranged side by side but in reverse relation, the charging end of one tunnel being at the discharging end of the 100 other, as is the case in the structure shown in Letters Patent issued to me August 13, 1918, No. 1,275,352. The inner wall, designated generally by the numeral 3, is common to both tunnels. The cooling zone of one tunnel is opposite the water smoking zone of the other and the firing zone of one is, in the embodiment illustrated, opposite the 105

preheating zone of the other. While the tunnels coact in their operation or there is a coacting relation between them there is no intercommunication or circulating connection whereby air or gases are admitted from one tunnel to the other.

At each end of the tunnels I preferably provide a transfer track 4 and a means for propelling the trucks through the tunnels, 10 shown conventionally at 5, the tunnel trucks being shown at 6 and their direction of travel indicated by the arrows in Figs. I, II, and III, and also by the numerals on the trucks.

15 The tunnels are provided with tracks 7 and sand guards 8 at each side. The trucks are preferably, in practice, advanced through the tunnels with a substantially continuous movement. Each tunnel has a 20 water smoking zone, a preheating zone, a firing zone, and a cooling zone.

In the main embodiment shown the gas producers 9 are connected to deliver to a series of three burners 10 into the firing zone 25 of the tunnel. These burners 10 are positioned in relation to circulating flues in the firing zone so as to produce, in effect, a plurality of sub-zones in the firing zone in which the temperatures may be varied or 30 modified to localize the highest temperature or vary as desired.

The arched roof 11 of the firing zone deflects and the flue connections draw the hot gases from the burners downwardly through 35 the stock, indicated at 12 on the truck 6 or about the containers,—see the arrows in Fig. VII. The inlets 13 of the vertical passages 14 of the flues are in about the plane of the truck platform. The passages 14 40 communicate at their upper ends with the horizontal flues 15, 16, 17, which, for convenience, may be designated firing zone flues. There are three of these firing zone flues in the embodiment illustrated,—see Figs. II 45 and X. These flues 15, 16, and 17, are connected to deliver to the horizontal flues 15', 16' and 17', which, for convenience in description, I designate as preheating flues, the preheating flues being disposed horizontally 50 at the outer sides of the preheating zones, designated generally by the numeral 18.

To facilitate circulation about these preheating flues and support the same I provide 55 on the outer walls of the funnels in front of the firing zones a plurality of vertical spaced flue supporting walls 19. These walls have aligned openings 20 therein to receive the ends of the flue sections 21,—see 60 Fig. I. These flue sections are formed of a material capable of withstanding the heat and at the same time having good radiating qualities, so that on the passage of gases and products of combustion to the stack 22 65 the greater portion of the heat is imparted

to the air within the preheating zone which circulates upwardly around the preheating flues and between the walls 19 and downwardly through the stock, as indicated by the arrows in Fig. IX.

70 At their discharge ends the flues are controlled by the slide dampers 23,—see Fig. VII.

By the adjustment of these dampers the circulation through the zone flues 15, 16 and 75 17 is controlled, that is, if the dampers are opened equally substantially an equal amount of draft will exist in these flues, thereby providing a substantially uniform distribution of heat throughout the firing 80 zone. For instance, if one of the dampers is closed the heat will be reduced in the zone controlled by it and intensified in the other zones. This enables the effective controlling of the firing zone to provide for 85 the subjecting of the ware in the firing zone to the highest temperature on its entrance to that zone or on its passage from it, or variable temperatures may be had, thus making the kiln adaptable to the particular 90 kind of ware or stock to be treated and to the results desired.

The burners 10 may be further controlled by the valves 24, shown conventionally in Fig. VII, and obviously by controlling the 95 supply of fuel, thus provide very simple, complete and accurate control for the kilns.

The stack 22 is provided with a damper 25,—see Fig. VII, providing still another control means.

100 To provide preheated air for the burners and to prevent the trucks becoming excessively heated in their passage through the heating zones and to protect the arches of the tunnels in the firing zones, I provide 105 air passages 26 having inlets at 27,—see Fig. IX. The air may be and preferably is supplied by the fan or blower 28. From this inlet point 27 the air travels toward the ends of the tunnels in both directions to the 110 passages 29 connected to the riser passages 30 which deliver to the return passages 31 in the tops of the tunnels,—see Fig. VI.

These return preheating passages prevent 115 the trucks and also the roofs or arches of the tunnels becoming unduly heated and the air is at the same time preheated. The delivery of this preheated air to the burners is controlled by the upper valves or dampers 24,—see Fig. VII.

In advance of each preheating zone is a water smoking zone in which the air is heated and circulated in the same manner as shown in my said patent, there being a series of circulating flues 32 in the central wall 125 opening at the top and bottom into the water smoking zone of one tunnel and having a wall 33 common to the cooling zone of the adjacent tunnel, so that a heating circulation is set up in the water smoking zone 130

of one tunnel and a cooling circulation in the cooling zone of the adjacent tunnel, as is shown by the arrows in Fig. VI.

The water smoking zones are provided 5 with vents 34.

In the modification shown in Figs. XII, XIII, I illustrate in conventional form an adaptation for burning oil, natural gas or like fuels.

10 Having described the structure generally, I will now briefly describe the operation: As stated, the tunnels are disposed in reverse relation with the charging end of one at the discharging end of the other. The trucks 15 are loaded and introduced one after the other and advanced by the propellers, the travel being preferably continuous and the speed depending upon the goods to be treated. The arrows and the numerals on 20 the trucks indicate the direction of movement. The trucks first pass through the water smoking zone where the water smoking is accomplished by the circulation of air heated and circulated by the cooling of 25 the ware in the other tunnel which is facilitated by the coacting relation of the tunnels. This transfer of heat sets up circulation in both tunnels so that the ware is effectively cooled and the water smoking 30 accomplished. By the time the ware reaches a preheating zone it is sufficiently heated so as not to be injured by the heat to which it is then subjected. The ware is heated in the preheating zone by the circulating air 35 only, the circulation and heating of which is accomplished by the preheating flues, as described.

From the preheating zone the ware passes into the firing zone which may be controlled as desired to localize the heat or 40 make it substantially uniform throughout the preheating zone or to secure sub zone variations, as may be desired.

From the firing zone the ware passes into 45 the cooling zone and on to the discharging end.

The length of the water smoking, preheating, firing and cooling zones may be varied as may be desired for the particular kind of 50 ware to be treated. The length of the kiln depends upon the goods to be fired and the capacity desired.

My improved kiln is very economical in the use of fuel, is easy to operate, and adaptable to produce various results which may be desired in kilns.

I have illustrated and described my improvements in an embodiment which I consider very satisfactory, although the parts 60 are largely shown in conventional form and, as stated, without an attempt to maintain relative proportions.

I have not attempted to illustrate or describe various adaptations and modifications 65 which might be desirable as I believe the

disclosure made will enable those skilled in the art to which my invention relates to embody or adapt the same as may be desired to meet the particular kind of stock to be treated and other special conditions. 70

Having thus described my invention, what I claim as new and desire to secure by Letter Patent, is:

1. The combination with a pair of tunnel kilns having a common inner wall and each comprising a water-smoking zone, a preheating zone, a firing zone, and a cooling zone, said kilns being disposed in reverse relation with the cooling zone of one opposite the water-smoking zone of the other and the firing zone of one opposite the preheating zone of the other, circulating flues opening at the top and bottom of the water smoking zone of each tunnel and arranged to receive heat from the cooling zone of the other tunnel, a plurality of heating burners for each firing zone disposed in the outer walls of the tunnels to deliver at the top thereof, a plurality of firing zone flues disposed below said burners one above the other and 75 having inlets disposed in alinement adjacent the bottoms of the tunnels, horizontally disposed preheating flues to which said firing zone flues deliver, stacks at the outer ends of said preheating zones to 80 which said preheating flues are connected, dampers for said stacks, dampers for said flues disposed at the stack ends thereof, air heating flues in the tops of said tunnels leading inwardly over the preheating and 85 firing zones to the burners, air flues in the bottoms of said tunnels leading outwardly from a central point and connected by riser flues to the outer ends of said air heating flues in the tops of said tunnels, and valves 90 for controlling the delivery of the air from said air heating flues and the delivery of the fuel to the burners. 95

2. The combination with a pair of tunnel kilns having a common inner wall and each comprising a water-smoking zone, a preheating zone, a firing zone, and a cooling zone, said kilns being disposed in reverse relation with the cooling zone of one opposite the water-smoking zone of the other and the firing zone of one opposite the preheating zone of the other, circulating flues opening at the top and bottom of the water smoking zone of each tunnel and arranged to receive heat from the cooling zone of the other tunnel, a plurality of heating burners for each firing zone disposed in the outer walls of the tunnels to deliver at the top thereof, a plurality of firing zone flues disposed below said burners one above the other and 100 having inlets disposed in alinement adjacent the bottom of the tunnels, horizontally disposed preheating flues to which said firing zone flues deliver, dampers for 105 said flues disposed at the stack ends thereof, air heating flues in the tops of said tunnels leading inwardly over the preheating and firing zones to the burners, air flues in the bottoms of said tunnels leading outwardly from a central point and connected by riser flues to the outer ends of said air heating flues in the tops of said tunnels, and valves 110 for controlling the delivery of the air from said air heating flues and the delivery of the fuel to the burners. 115

3. The combination with a pair of tunnel kilns having a common inner wall and each comprising a water-smoking zone, a preheating zone, a firing zone, and a cooling zone, said kilns being disposed in reverse relation with the cooling zone of one opposite the water-smoking zone of the other and the firing zone of one opposite the preheating zone of the other, circulating flues opening at the top and bottom of the water smoking zone of each tunnel and arranged to receive heat from the cooling zone of the other tunnel, a plurality of heating burners for each firing zone disposed in the outer walls of the tunnels to deliver at the top thereof, a plurality of firing zone flues disposed below said burners one above the other and 120 having inlets disposed in alinement adjacent the bottom of the tunnels, horizontally disposed preheating flues to which said firing zone flues deliver, dampers for said flues, air heating flues in the tops 125

of said tunnels leading inwardly over the preheating and firing zones to the burners, air flues in the bottoms of said tunnels leading outwardly from a central point and connected by riser flues to the outer ends of said air heating flues in the tops of said tunnels, and valves for controlling the delivery of the air from said air heating flues and the delivery of the fuel to the burners.

10 3. The combination with a pair of tunnel kilns having a common inner wall and each comprising a water-smoking zone, a pre-heating zone, a firing zone, and a cooling zone, said kilns being disposed in reverse
15 relation with the cooling zone of one opposite the water-smoking zone of the other and the firing zone of one opposite the preheating zone of the other, circulating flues opening at the top and bottom of the water
20 smoking zone of each tunnel and arranged to receive heat from the cooling zone of the other tunnel, a plurality of heating burners for each firing zone disposed in the outer walls of the tunnels to deliver at the top
25 thereof, a plurality of firing zone flues disposed below said burners one above the other and having inlets disposed in alignment adjacent the bottoms of the tunnels, horizontally disposed preheating flues to
30 which said firing zone flues deliver, stacks at the outer ends of said preheating zones to which said preheating flues are connected, dampers for said stacks, and dampers for said flues disposed at the stack ends thereof.
35 4. The combination with a pair of tunnel kilns having a common inner wall and each comprising a water-smoking zone, a pre-heating zone, a firing zone, and a cooling zone, said kilns being disposed in reverse
40 relation with the cooling zone of one opposite the water-smoking zone of the other and the firing zone of one opposite the preheating zone of the other, circulating flues opening at the top and bottom of the water smok-
45 ing zone of each tunnel and arranged to receive heat from the cooling zone of the other tunnel, a plurality of heating burners for each firing zone disposed in the outer walls of the tunnels to deliver at the top
50 thereof, a plurality of firing zone flues disposed below said burners one above the other and having inlets disposed in alignment adjacent the bottoms of the tunnels, horizontally disposed preheating flues to
55 which said firing zone flues deliver, and dampers for said flues.

5. The combination with a pair of tunnel kilns having a common wall and each comprising a water-smoking zone, a preheating zone, a firing zone, and a cooling zone, said kilns being disposed in reverse relation, a plurality of heating burners for each firing zone disposed in the outer walls of the tunnels to deliver at the top thereof, a plurality of firing zone flues disposed below

said burners one above the other and having inlets disposed in alignment adjacent the bottoms of the tunnels, horizontally disposed preheating flues to which said firing zone flues deliver, stacks at the outer ends 70

of said preheating zones to which said pre-heating flues are connected, dampers for said stacks, dampers for said flues disposed at the stack ends thereof, air heating flues in the tops of said tunnels leading inwardly over 75 the preheating and firing zones to the burners, air flues in the bottoms of said tunnels leading outwardly from a central point and connected by riser flues to the outer ends of said air heating flues in the tops of said 80 tunnels, and valves for controlling the delivery of the air from said air heating flues and the delivery of the fuel to the burners.

6. The combination with a pair of tunnel kilns having a common inner wall and each comprising a water smoking zone, a preheating zone, a firing zone, and a cooling zone, said kilns being disposed in reverse relation, a plurality of heating burners for each firing zone disposed in the outer walls of the tunnels to deliver at the top thereof, a plurality of firing zone flues disposed below said burners one above the other and having inlets disposed in alignment adjacent the bottoms of the tunnels, horizontally disposed preheating flues to which said firing zone flues deliver, dampers for said flues, air heating flues in the tops of said tunnels leading inwardly over the pre-heating and firing zones to the burners, air flues in the bottom of said tunnels leading outwardly from a central point and connected by riser flues to the outer ends of said air heating flues in the tops of said tunnels, and valves for controlling the delivery of the air from said air heating flues and the delivery of the fuel to the burners. 105

7. The combination with a pair of tunnel kilns having a common inner wall and each comprising a water-smoking zone, a pre-heating zone, a firing zone, and a cooling zone, said kilns being disposed in reverse relation, a plurality of heating burners for each firing zone disposed in the outer walls of the tunnels to deliver at the top thereof, a plurality of firing zone flues disposed below said burners one above the other and having inlets disposed in alignment adjacent the bottoms of the tunnels, horizontally disposed preheating flues to which said firing zone flues deliver, stacks at the outer ends of said preheating zones to which said preheating flues are connected, dampers for said stacks, and dampers for said flues disposed at the stack ends thereof. 110 115 120 125

8. The combination with a pair of tunnel kilns having a common inner wall and each comprising a water-smoking zone, a preheating zone, a firing zone, and a cooling zone, said kilns being disposed in reverse relation, 130

- a plurality of heating burners for each firing zone disposed in the outer walls of the tunnels to deliver at the top thereof, a plurality of firing zone flues disposed below said burners one above the other and having inlets disposed in alignment adjacent the bottoms of the tunnels, horizontally disposed preheating flues to which said firing zone flues deliver, and dampers for said flues.
10. The combination with a pair of tunnel kilns having a common inner wall and each comprising a water-smoking zone, a preheating zone, a firing zone, and a cooling zone, said kilns being disposed in reverse relation, with the charging end of one at the discharging end of the other, a heating means for each firing zone delivering at the tops of the tunnels, a plurality of firing zone flues connected in series at the bottom thereof, and preheating flues to which said firing zone flues deliver, stacks at the outer ends of said preheating zones to which said preheating flues are connected, dampers for said stacks, dampers for said flues, air heating flues in the tops of said tunnels leading inwardly to the burners, air flues in the bottoms of said tunnels leading outwardly from a central point and connected to the outer ends of said air heating flues in the tops of the said tunnels, and valves for controlling the delivery of the air from said air heating flues.
10. The combination with a pair of tunnel kilns having a common inner wall and each comprising a water-smoking zone, a preheating zone, a firing zone, and a cooling zone, said kilns being disposed in reverse relation, with the charging end of one at the discharging end of the other, a heating means for each firing zone delivering at the tops of the tunnels, a plurality of firing zone flues connected in series at the bottom thereof of means for independently controlling, said flues, air heating flues in the tops of said tunnels leading inwardly to the burners, air flues in the bottoms of said tunnels leading outwardly from a central point and connected to the outer ends of said air heating flues in the tops of said tunnels, and valves for controlling the delivery of the air from said air heating flues.
11. The combination with a pair of tunnel kilns having a common inner wall and each comprising a water-smoking zone, a preheating zone, a firing zone, and a cooling zone, said kilns being disposed in reverse relation, with the charging end of one at the discharging end of the other, a heating means for each firing zone delivering at the tops of the tunnels, a plurality of firing zone flues connected in series at the bottom thereof, preheating flues to which said firing zone flues deliver, stacks at the outer ends of said preheating zones to which said preheating flues are connected, dampers for said stacks, and dampers for said flues.
12. The combination with a pair of tunnel kilns having a common inner wall and each comprising a water-smoking zone, a preheating zone, a firing zone, and a cooling zone, said kilns being disposed in reverse relation, with the charging end of one at the discharging end of the other, a heating means for each firing zone delivering at the tops of the tunnels, a plurality of firing zone flues connected in series at the bottom thereof, and dampers for said flues.
13. The combination with a pair of tunnel kilns having a common inner wall and each comprising a water-smoking zone, a preheating zone, a firing zone, and a cooling zone, said kilns being disposed in reverse relation, with the charging end of one at the discharging end of the other, means whereby the cooling of the ware in the cooling zone of one tunnel is utilized to heat and circulate the air in the water smoking zone of the other, a heating means for each firing zone delivering at the tops of the tunnels, a plurality of firing zone flues connected in series at the bottom thereof, stacks to which preheating flues are connected, and dampers for said stacks.
14. The combination with a tunnel kiln comprising a firing zone and a preheating zone, a plurality of heating burners for said firing zone disposed to deliver at the top thereof, a plurality of firing zone flues disposed below said burners one above the other and having inlets adjacent the bottom of the tunnel, horizontally disposed preheating flues for said preheating zone and to which said firing zone flues deliver comprising spaced vertical walls provided with aligned openings and flue sections supported thereby, a stack to which said preheating flues are connected, a damper for said stack, dampers for said flues disposed at the stack ends thereof, an air heating flue in the top of said tunnel leading inwardly over the preheating and firing zones to the burners, an air flue in the bottom of the tunnel leading outwardly and connected at its outer end to the outer end of said air heating flue in the top of said tunnel, and valves for controlling the delivery of air from said air heating flue and delivery of the fuel to the burners.
15. The combination with a tunnel kiln comprising a firing zone and a preheating zone, a plurality of heating burners for said firing zone disposed to deliver at the top thereof, a plurality of firing zone flues disposed below said burners one above the other and having inlets adjacent the bottom of the tunnel, horizontally disposed preheating flues for said preheating zone and to which said firing zone flues deliver comprising spaced vertical walls provided with aligned openings and flue sections supported thereby, a stack to which said preheating

- flues are connected, a damper for said stack, and dampers for said flues disposed at the stack ends thereof.
16. The combination with a tunnel kiln comprising a firing zone and a preheating zone, a plurality of heating burners for said firing zone disposed to deliver at the top thereof, a plurality of firing zone flues disposed below said burners one above the other and having inlets adjacent the bottom of the tunnel, horizontally disposed preheating flues for said preheating zone and to which said firing zone flues deliver, comprising spaced vertical walls provided with alined openings and flue sections supported thereby, dampers for said flues disposed at the stack ends thereof, an air heating flue in the top of said tunnel leading inwardly over the preheating and firing zones to the burners, an air flue in the bottom of the tunnel leading outwardly and connected at its outer end to the outer end of said air heating flue in the top of said tunnel, and valves for controlling the delivery of air from said air heating flue and delivery of the fuel to the burners.
17. The combination with a tunnel kiln comprising a firing zone and a preheating zone, a plurality of heating burners for said firing zone disposed to deliver at the top thereof, a plurality of firing zone flues disposed below said burners one above the other and having inlets adjacent the bottom of the tunnel, horizontally disposed preheating flues for said preheating zone and to which said firing zone flues deliver comprising spaced vertical walls provided with alined openings and flue sections supported thereby, and dampers for said flues disposed at the stack ends thereof.
18. The combination with a tunnel kiln comprising a firing zone and a preheating zone, a heating means for said firing zone, a plurality of firing zone flues opening in series into said firing zone, preheating flues for said preheating zone to which said firing zone flues deliver, a stack to which said preheating flues are connected, a damper for said stack, and dampers for said flues.
19. The combination with a tunnel kiln comprising a firing zone and a preheating zone, a heating means for said firing zone, a plurality of firing zone flues opening in series into said firing zone, preheating flues for said preheating zone to which said firing zone flues deliver, dampers for said flues, an air heating flue in the top of said tunnel leading inwardly to the heating means, and an air flue in the bottom of the tunnel leading outwardly and connected at its outer end to the outer end of said air heating flue in the top of said tunnel.
20. The combination with a tunnel kiln comprising a firing zone and a preheating zone, a heating means for said firing zone, a plurality of firing zone flues opening in series into said firing zone, preheating flues for said preheating zone to which said firing zone flues deliver, a stack to which said preheating flues are connected, a damper for said stack, and dampers for said flues.
21. The combination with a tunnel kiln comprising a firing zone and a preheating zone, a heating means for said firing zone, a plurality of firing zone flues opening in series into said firing zone, preheating flues for said preheating zone to which said firing zone flues deliver, and dampers for said flues.
22. The combination with a tunnel kiln comprising a firing zone, a plurality of heating burners for said firing zone delivering at the top thereof, a plurality of firing zone flues opening in series into said firing zone at the bottom thereof, and means for independently controlling said flues.
23. The combination with a tunnel kiln comprising a firing zone, a heating means for said firing zone, a plurality of firing zone flues opening in series into said firing zone, and means for independently controlling said flues.
24. The combination with a tunnel kiln comprising a firing zone and a preheating zone, a heating means, an air heating flue in the top of said tunnel leading inwardly over the preheating and firing zone to the burners, an air flue in the bottom of the tunnel leading outwardly and connected at its outer end to the outer end of said air heating flue in the top of said tunnel, and valves for controlling the delivery of air for said air heating flues and delivery of the fuel to the burners.
- In witness whereof, I have hereunto set my hand and seal in the presence of two witnesses.
